UNITED STATES PATENT OFFICE.

GEORGE K. REIST, OF HARRISBURG, PENNSYLVANIA.

FLOATING STORAGE-PORT.

1,397,385.

Specification of Letters Patent.

Patented Nov. 15, 1921.

Application filed January 21, 1920. Serial No. 353,060.

To all whom it may concern:

Be it known that I, GEORGE K. REIST, a citizen of the United States, residing at Harrisburg, in the county of Dauphin and 5 State of Pennsylvania, have invented certain new and useful Improvement in Floating Storage-Ports, of which the following is a specification.

This invention relates to means for storing canoes, motor boats and the like upon a floating structure which I term a floating storage port.

One of the important city planning and park design problems that is presented under a wide variety of conditions is the question of housing canoes and boats and providing for bathers. The variety of conditions presented is represented fairly well by the following observations that have come 20 into my experience.

At Lake Minnetonka, Minnesota, the pressure of the expanding ice during periods of extreme cold, is so great as to crowd the ice against the shore to the extent even of forcing up soil ridges along shore in places. This condition makes it impracticable to maintain boat-houses, as the structure or 25 its support may be crushed by the ice pressure and movement. Where such structures do exist, a channel is sawed in the ice around the structure to give protection from ice expansion. The alternative puts the houses back from shore above ice level, requiring the pulling off over long run-ways.

In the Susquehanna river at Wilkes-Barre and Harrisburg, Pennsylvania, there are periods of sudden rise that makes a difference in the river elevation of 20 or 30 feet, or more, and also when the ice is 30 breaking up it sweeps by and piles onto the shore in such a way as to do injury to all but the most substantial structures. The evidence of the power of the ice is shown on the up-river side of trees in such rivers 45 by the great scars from which the bark has been battered.

Boat-houses on such rivers must be carried so far up on the bank that a long and tiresome pull is required to convey boats 50 to and from the water's edge. Further-

more, in very high water even these houses are flooded and they are not conveniently located for motor or other heavy boats.

Farther south where there is less ice there is likely to be a much greater rise in the river, amounting in some instances to 60 or 70 feet, which makes boat-houses near the shore quite impracticable.

In the study of the plan for Harrisburg, Pa., this question of providing boat-houses 60 and dressing-rooms for those who would use 65 the river basin for recreation purposes was one of the difficult problems. This river basin was established a few years ago by the construction of the dam across the Susquehanna, a little below the center of the 70 city.

The conditions in the Susquehanna as stated above, made it impracticable to establish boat-houses or bath-houses along the 70 shore. The existing boat-houses are far up on the bank in order to be above the extreme flood lever, as is indicated on the accompanying illustration. It will be observed that boats must be carried back and 75 forth to the boat-house for storage. During the summer platforms must be used for boat landing, these platforms being made necessary by frequent fluctuation in river level, and must be moved to suit height or river. 80

My present invention has for its object to provide a structure which shall meet all of the requirements above enumerated and which, while capable of being constructed at comparatively small cost, has 85 from practice been found to be most satisfactory and efficient.

My structure or floating storage port is so arranged that boats may be taken in from the end or side of the structure and 90 placed on racks, or otherwise supported, and piled two, three, four or more in height.

The device used to hold these ports in place during the fluctuations in water level, is a heavy rod or pipe that is driven in or 95 anchored at the bottom and passes through the boat platform so it can move up and down without changing position, as the water levels fluctuate. There are also other devices used in anchoring to safe guard 100

against swift water. In winter these ports are anchored where the dressing-rooms can be utilized by skaters, so they have an all-the-year period of usefulness. In devices of 5 this character compactness is essential in order that every inch of space may be utilized. In order to do this I arrange the compartments and lockers in parallel relation with separate access to each set of 10 compartments.

Other objects and advantages of the invention will hereinafter appear and the novel features thereof will be particularly pointed out in the appended claims.

15 The invention is capable of embodiment in a variety of forms, dependent, in a great measure, upon the conditions and the requirements, some of which forms, being those which I have found from practical 20 demonstration to be very desirable, being herein shown as illustration of some of the ways in which my invention can be carried out.

Such forms are clearly illustrated in the 25 accompanying drawings, which, with the numerals of reference marked thereon, form a part of this specification, and in which—

Figure 1 is a side elevation with portions broken away and parts in section illustrating 30 one form of my floating storage having an upper deck member used for pleasure.

Fig. 2 is a horizontal section showing the floor plan with lockers and partitions for the canoes being placed crosswise either on 35 the floor or hangers or racks.

Fig. 3 is a horizontal section showing another floor plan with dressing lockers, gangway, with the canoes placed crosswise and a sliding platform to facilitate the taking 40 of the canoes in and out of the canoe lockers.

Fig. 4 is a horizontal section showing the floor plan wherein the canoes are placed lengthwise in storage, showing a stairway leading to the upper deck.

45 Fig. 5 is an enlarged detail in elevation, showing one of the canoes in position.

Fig. 6 is a sectional detail to illustrate another arrangement of lockers.

Like numerals of reference indicate like 50 parts throughout the several views.

In carrying out my invention, I employ a floatable dock or sub-structure 1 of any desired shape, preferably, though not necessarily, substantially rectangular in form, as 55 seen in the various views, and of a size dependent upon the required capacity of the floatable storage port. This sub-structure may be of any desired construction having a suitable floor 2, and the floor space may be 60 subdivided in a variety of ways varying with the different conditions or requirements. In Fig. 2 I have shown this space subdivided with alternating aisles 3 and storage spaces 4 for the canoes or other boats. In this

present arrangement, there is a single space 65 4 devoted for canoes at each end and two spaces 4 between each two aisles. These spaces 4 between each two aisles may be subdivided by a partition or the like 5 extending longitudinally of the spaces, that is transversely of the length of the device, and, if desired, these spaces may be further divided by means of partitions 6 extending lengthwise of the device and at right angles to the partitions 5. These partitions may 70 be of any nature—skeleton or latticed or merely rods or bars securely affixed in position by any well-known way.

At one end of each aisle is a door 7, while at the other end of each aisle are two lockers 8, each provided with a door 9 whereby access may be had to the said lockers from the aisles.

At the ends of the spaces 4 for the canoes are lockers 10 access to which is had through 80 doors 11 opening into the aisles, one upon either side thereof, as seen clearly in Fig. 2.

The floating dock or sub-structure 1 is designed to be secured or anchored in the desired position so as to allow the same to rise 90 and fall with the tide or with the movement of the water occasioned by the waves. One efficient way I have found to be to provide the sub-structure 1 with guide members or eyes 12, as seen in Fig. 2, through which 95 loosely pass heavy rods or the like 13, which are designed to be securely anchored in the bed of the stream, being of sufficient length to permit of the rising of the dock to the required height without danger of displacement of the rods. Fig. 1 clearly illustrates the manner in which the rods are arranged, the rod in this instance, however, being passed through an opening in the bottom of the sub-structure, this being one of the modified ways in which the rod may be disposed, depending upon the form of floating storage port, such for instance, as seen in Fig. 4 where the rods are, as shown in Fig. 1, disposed within the outer or boundary line 100 of the dock or sub-structure and passed loosely through the openings 14 therein. In this form, Fig. 4, the sub-structure 1 is provided with a gangway 15 extending entirely around the same and a door 16 is provided at 115 each end of the aisles 17 which extend lengthwise of the structure, with canoe spaces 18 upon opposite sides of each aisle. These canoe spaces 18 may be divided lengthwise by suitable partitions or the like 19, and the 120 space between the two aisles 17 may be further divided by a longitudinal partition 20, or not, as may be deemed most expedient. In this form, as well as that shown in Fig. 2, the canoe spaces may be provided 125 with hangers or may be arranged in tiers, three or four in height so as to accommodate the greatest number of canoes or other boats.

Fig. 5 illustrates one form of disposition of the canoes 21 in tiers, and this view also indicates how each canoe space may be provided with a door 22 having a lock 23 whereby each canoe may be individually inclosed and locked within its space.

In Fig. 3 the sub-structure or dock 1 is provided with a gangway 24 all around the same and at one side with an extension plat-
10 form or the like 25 upon which is supported a guide rail 26 for a sliding platform 27 which may be easily moved therealong so that the canoes may be more readily taken in or out of their spaces. In this form the 15 floor space is divided into individual canoe spaces 28, each space having a door 29 and at the opposite end of each space a locker 30, each locker being provided with a separate door 31, as shown. These spaces 28 may 20 be arranged to receive three, four or more canoes.

The dressing lockers of my floating storage port may be variously arranged, Fig. 3 showing one form of arrangement wherein 25 the lockers may be made of varying size, for instance, the lockers 32 are larger than the lockers 30, while the lockers 33 are made of still greater capacity. These are given merely as instances of the different arrangements which may be resorted to dependent upon the requirements of the apparatus using the same.

Any or all of the different forms of structure as hereinbefore described may be of a 35 single deck or each or any of them may be provided with an upper deck. In Fig. 1 I have shown such upper deck 34 mounted upon the roof 35 covering the canoe spaces and aisles referred to and this upper desk 40 provided with a roof or canopy 36 supported in any suitable way as by the posts or the like 37. This upper deck may be used for pleasure or dancing or any other purpose and may or may not be provided with suitable 45 seats.

If desired, the gangway may be, in a measure, supported by suitable means, as shown at 38, and at the ends of the gangway there may be provided suitable ornaments, as shown at 39, supporting flower-pots 50 or the like 40 in which may be placed suitable plants to add to the attractiveness of the structure. Suitable stairways *a* are provided leading to the upper deck.

Various modifications in arrangements of the dressing rooms, etc., may be resorted to. For instance, if desired, the dressing rooms may be arranged in the center instead of at the ends. The gangways may be portable. 55 The lockers may be disposed otherwise than hereinbefore described and illustrated, for instance, as shown in Fig. 6 the lockers may be arranged in sets of three instead of two. As seen in said Fig. 6, the center locker 41

is provided with a door 42 whereby access 65 thereto may be had from the gangway or the outer side of the dock or substructure 1, while the other two lockers or dressing rooms 43 are provided with doors 44 at the sides adjacent the doors 45. By this ar- 70 arrangement the lockers or compartments 43 may be used for dressing rooms and the locker 41 may serve as storage for the oars or other accessories of the canoe, or accessories of a motor-boat.

A variety of other arrangements and dis- 75 positions of the canoe spaces and lockers or dressing rooms may be provided.

From the foregoing, it will be seen that I have devised a simple, yet complete struc- 80 ture for the purpose specified, with accom- modations for bathing or skating, together with provision for the storage of canoes or other boats, and which structure can be mov- able or stationary floating and which can be 85 placed and retained in any desired position during the summer or winter months. It will also be evident that while the struc- tural embodiments of my invention as here- 90 in shown and described are what I, at the present time, consider preferable, the same is subject to variations and modifications in detail, proportions of parts, arrangement, disposition of the canoe spaces and lockers, without departing from the spirit of the in- 95 vention or sacrificing any of its advantages. I, therefore, do not intend to restrict my- self as to the particular construction and arrangement of parts hereinbefore disclosed, but reserve the right to make such changes, 100 variations and modifications as come prop- erly within the scope of the protection prayed.

What is claimed as new is:—

1. A floating storage port comprising a 105 floatable substructure, a super-structure thereon, inset from a side edge of the sub-structure to provide a gang-way, storage elements extending from one side of the super-structure to the other and arranged in par- 110 allel relation, and ports in the side of the super-structure adjacent the gang-way afford- ing access to the storage elements.

2. A floating storage port comprising a floatable substructure, and a super-struct- 115 ure thereon sub-divided to form compactly-arranged storage compartments in parallel relation and lockers, said sub-structure hav- ing a gang-way for access to said compart- ments and lockers.

3. A floating storage port comprising a sub-structure, a super-structure thereon inset from a side edge of the sub-structure to pro- 120 vide a gang-way, storage elements extending from one side of the super-structure and ar- ranged in parallel relation with ports in the side of the super-structure adjacent to the gang-way affording access to each set of

storage elements, and anchoring means to permit vertical movement only of the said floating storage port.

4. A floating storage port comprising a floatable substructure, a super-structure thereon sub-divided to form compactly arranged storage compartments in parallel re-

lation, said substructure having a gang-way to afford separate access to each of the sets of storage compartments through ports in 10 said super-structure, and a canoe-loading platform movable along said gang-way.

In testimony whereof I affix my signature.

GEORGE K. REIST.
